UNITED STATES PATENT OFFICE

JESSE FULENWIDER AND HARRY FULENWIDER, OF SAVANNAH, GEORGIA, ASSIGNEES
TO THE SOUTHERN STATES IRON ROOFING COMPANY, INC., OF SAVANNAH, GEORGIA

ROOFING FASTENER

Application filed July 29, 1929. Serial No. 381,855.

Our present invention has reference to fastening devices for sheet metal roofing, and particularly to that type of device which is used for holding in place the ends of galvanized sheet roofing arranged where one or more sheets must be used from comb of the roof to the eave of the roof, and also for holding in place or locking down the ends of the sheets of roofing on the bottom course, 10 where the ends of the sheets of roofing touch the eaves of the roof.

The primary object of the invention is the provision of simple means for holding the ends of the sheets in place and provide for 15 the expansion and contraction of the metal roofing sheets and to prevent water from blowing up under the ends of the metal roofing during hard hail and wind storms.

To the attainment of the foregoing and 20 other objects which will present themselves the invention consists in the improvement hereinafter described and definitely claimed.

In the drawing:

Figure 1 is a plan view of a metal sheet 25 covered roof having the ends of the sheets connected in accordance with this invention.

Figure 2 is a sectional view approximately on the line 2—2 of Figure 1.

Figure 3 is a perspective view of one of the 30 fasteners.

While in the drawing we have illustrated our improvement in connection with metal roofing sheets 1 provided with central longitudinally extending substantially cross sectional outstanding ribs and with similar ribs adjacent to the edges thereof, obviously the device may be employed with other types of roofing sheets. As is well known the roofing sheets are arranged over the roof sheathing 35 so that the ends thereof are overlapped from four to 12 inches over each other. Where these laps are made the sheets of roofing do not lie smooth. They have a decided tendency for the flat part of the end of the upper sheet to "pucker" up and buckle, which leaves a gapping space or spaces where the end laps are made. In blowing rains it is an easy matter for water to blow up under these open spaces and cause the roof to leak. Also these 45 gappings and buckled places are unsightly 50

and tend to spoil the entire roof. Obviously the edges of the sheets at the lapping portions thereof could be nailed to the wood sheathing strips under the sheets of roofing and thus will in some degree tend to close up the distortion and buckling of the ends of the roofing sheets, but the nailing of the edges would not completely close up the irregularities between the sheets and besides it has been found a very bad practice to drive nails 55 through the flat parts of galvanized metal roofing sheets for the reason that when the nails are driven through such parts of the metal the heat from the sun and the shrinkage of the sheathing lumber underneath, almost invariably causes the nails to loosen and rise up and the openings in the sheets closed by the nails provide passages for water which obviously causes the leaking of the roof.

In carrying out our invention we employ 70 comparatively narrow plates 2 which, when employed in connection with the form of roof disclosed by the drawing are centrally formed with upstanding ribs 3 by grooving or corrugating the said plates. Each plate 2 75 is provided with openings 4 for the reception of securing nails or the nails may be driven directly through the plates. The outer and lower edge of each of the plates is formed with an equal number of spaced 80 extensions which are bent over the plate proper to provide the same with cleats 5. By reference to Figure 2 of the drawing it will be seen that the plates 2 are arranged over and secured to one of the roofing sheets 85 1, at a point below the edge thereof to be lapped by the next roofing sheet. When the next roofing sheet is arranged over the first mentioned roofing sheet and is received in the cleats 5 and likewise has its central rib received in the rib 3 of the said sheet 2 the cleats 5 are hammered over the overlapping 90 roofing sheet it, of course, being understood that the plate 2 is nailed to the underlying sheet. 95

We have found, however, that a more perfect joint can be obtained by forming the plates 2 with central longitudinally extending outwardly projected cross sectionally rounded ribs 7 over which the roofing sheets 100

are inserted prior to the hammering of the cleats 5 thereagainst. Such hammering of the cleats 5 will cause the sheets 1 to bend against the longitudinal ribs 7 and to be 5 tightly contacted by at least the outer faces of the ribs and thereby afford a positive locking joint. Also we preferably adhesively or otherwise secure to the under face of the plates 2 compressible strips 6, as disclosed by 10 the drawing.

Having described the invention, we claim:

A roofing comprising metal sheets which have their edges disposed inlapping relation, a plate arranged transversely of and adjacent to the end of each metal sheet, nailed to the sheets and to the roofing, the said plate having its outer edge formed with bendable cleats designed to receive therein and to be bent over the edge of the overlapping plate and to be hammered thereagainst, and said plate being centrally formed with a longitudinally extending outwardly projecting cross sectionally rounded rib for contacting engagement with and for crimping 25 the edge of the plate arranged thereover, and said plate having an inner compressible facing.

In testimony whereof we affix our signatures.

30 HARRY FULENWIDER.
